UNITED STATES PATENT OFFICE.

ABRAM C. MOTT, OF PHILADELPHIA, PENNSYLVANIA.

STEAM-GENERATOR.

SPECIFICATION forming part of Letters Patent No. 537,350, dated April 9, 1895.

Application filed December 14, 1894. Serial No. 531,839. (No model.)

To all whom it may concern:

Be it known that I, ABRAM C. MOTT, a citizen of the United States, residing in Philadelphia, Pennsylvania, have invented certain 55
5 Improvements in Steam-Generators, of which the following is a specification.

The object of my invention is to construct a vertical steam generator of a series of sections mounted one upon another in a manner 10 which will expose the greatest amount of surface to the action of the products of combustion.

My invention also relates to the special construction of some of the parts, reference being had to the accompanying drawings, in 15 which—

Figure 1 is a perspective view of my improved steam generator. Fig. 2 is a vertical sectional view on the line 2—2, Fig. 3. Fig. 20 3 is a sectional plan view on the line 3—3, Fig. 2. Fig. 4 is an inverted plan view of the dome section. Fig. 5 is a sectional perspective view showing the arrangement of the water sections. Fig. 6 is a detached perspective view 25 of a number of the parts of the furnace.

A is the fire pot mounted in any suitable manner upon the base section A' of the furnace. The fire pot is made hollow forming a water chamber a and has an extended rim a' 30 forming an enlargement of the water chamber and supporting the ring sections described hereinafter. Projecting inwardly from the upper portion of the fire pot are a series of hollow fingers a² communicating with the water chamber a and each finger is, in the present instance, flat on the under side and curved on the upperside so as to prevent the accumulation 35 of soot and yet not interfere with the coaling of the furnace.

40 Mounted on the fire pot A is a ring B made as shown in Fig. 6, having a double rim b in which are the flues c.

b' represents a series of spokes extending to a hub b² and between these spokes b' are 45 short spokes b³ which communicate with the spokes b' by necks b⁴. Between the several spokes are passages c' for the products of combustion. Both the upper and lower surfaces of the spokes are beveled as shown in 50 Figs. 5 and 6, to prevent the accumulation of soot and to present the surface of the sections

to the action of the products of combustion without interfering with the draft. The water circulates in each section through the hub, spokes and rim and one or more sections similar in form to the section B can be mounted above the said section as illustrated in Fig. 2, and these sections can communicate through the hubs b² and passages b⁵. The hub of the lower section is closed and the hub of the upper section communicates with the crown section D, described hereinafter.

The spokes of the sections B B are placed at equal distances apart, except at one point x where the short spokes b³ are dispensed 65 with. The object of this arrangement is to so form the sections that when one section is placed upon another the upper section can be adjusted so that its spokes will be above the passages of the lower section, as clearly 70 shown in the perspective view Fig. 5, so that the course of the products of combustion will be circuitous in its passage through the sections, thus insuring the proper heating of the sections.

75 The sections are held together in the present instance, by tie bolts E, which extend through the rim a' of the fire pot and through the passages b⁵ in the ring sections and through the dome section. Packing may be 80 inserted between the several sections so as to make them water and gas tight or the joints may be simply ground joints.

I prefer to form a tongue and groove joint between the sections as indicated in the several figures, which joint may be filled with suitable cement if necessary. Nipples may also be used as shown by dotted lines in Fig. 2 instead of the bolts or both may be used if desirable.

85 While the spokes of the ring sections may be beveled in any suitable manner so as to prevent the accumulation of soot, I preferably make the spokes double convex in cross section, the long axis being vertical as I find this arrangement gives the best circulation 95 and the parts are considerably strengthened as each ring section is preferably made in a single casting, although this is not absolutely necessary.

90 D is the crown section having the dome d and the corrugated base d' and these corrugated

gations are broken at intervals by channels d^2 , Fig. 4, which carry off any water that may accumulate in the corrugations when the water is drawn off below the line of the dome. 5 In the dome is a passage d^3 directly above each channel c in the ring section so that a cleaning tool can be inserted through this passage to clean the channels. These openings are provided with suitable covers. The 10 crown section being made in a single casting is stiffened by the direct flue casing d^5 , which is formed in the crown section, as clearly shown in Fig. 2. This flue communicates with a pipe M' entering the smoke pipe M , as 15 clearly illustrated in said figure. The crown section may be stiffened by columns extending from the corrugated base to the dome if found necessary. The pipe M extends to the fire pot section and communicates with a passage C at this point.

F is a cast metal casing inclosing the lower portion of the furnace and having therein the fire door f and clean out openings f', f'' .

G is a casing mounted on the casing F and 25 inclosing the ring sections leaving a dead space c^2 , which communicates at the base with the annular passage C so that while the products of combustion do not circulate through this passage the air therein is kept 30 at a certain temperature and acts as a protector for the ring sections.

The water inlet pipe i communicates with the fire pot section and the steam pipes i' communicate with the dome section.

35 While I have described my invention as a steam generator for heating purposes it will be understood that it may be used as a hot water heater or a steam generator for power purposes without departing from my invention, and that one or more ring sections may be used depending altogether upon the character of the work in which it is to be employed.

I claim as my invention—

1. The combination in a steam generator, 45 of the hollow fire pot section, having disconnected hollow fingers projecting over the fire, with a series of hollow sections mounted above the fire pot and communicating therewith, substantially as described.

50 2. The combination of the fire pot, a series of hollow ring sections having rims and spokes, one of said spokes being narrower than the others, whereby the sections can be so arranged that the spokes of one section will alternate with the spokes of another section, substantially as described.

55 3. The combination in a steam generator, of the hollow fire pot section, having discon-

nected hollow fingers projecting inwardly around its upper edge, two or more ring sections each having a series of spokes, one set of spokes alternating with the other said ring sections being connected to the hollow fire pot, with a dome section, substantially as described. 60

65 4. The combination of the fire pot section, having a hollow flange at its upper edge, and inwardly projecting fingers, with ring sections mounted on the flange of the fire pot section and communicating therewith, spokes in said ring section and channels in the rim of each ring section and in the flange of the fire pot section, a dome section mounted above the ring section, substantially as described.

70 5. The combination of the fire pot section, the ring sections, a dome section having a crown and a corrugated base, said dome section communicating with the ring section, substantially as described.

75 6. The combination in a steam generator, of the fire pot section, one or more ring sections mounted thereon, the dome section mounted on the upper ring section and communicating therewith, the base of said dome section being corrugated and having radial 80 channels therein, substantially as described.

7. The combination in a steam generator, of the fire pot and dome, with a ring section consisting of a rim having channels therein and spokes and a hub, some of said spokes 90 extending to the hub from the rim while others extend part way from the rim to the hub, and connected to the other spokes, substantially as described.

8. The combination of the fire pot, ring sections and dome, forming the generator, with an outer casing surrounding the ring sections, and forming a smoke passage at the base and a dead air space around the ring sections, said space communicating with the smoke passage, 95 substantially as described.

9. The combination of the fire pot and ring sections, and base with a cast metal casing above the base and surrounding the fire pot and forming therewith a smoke passage, said 105 casing having clean out openings communicating with the smoke passage and having a fire door opening therein, substantially as described.

110 In testimony whereof I have signed my name to this specification in the presence of two subscribing witnesses.

ABRAM C. MOTT.
